UNITED STATES PATENT OFFICE.

MARSHALL F. APGAR AND CHARLES B. ANDREWS, OF HIGH BRIDGE, NEW JERSEY,
ASSIGNORS TO TAYLOR-WHARTON IRON & STEEL CO., OF HIGH BRIDGE, NEW
JERSEY, A CORPORATION OF NEW JERSEY.

DREDGE-TUMBLER.

1,271,990.

Specification of Letters Patent.

Patented July 9, 1918.

Application filed October 5, 1917. Serial No. 194,921.

To all whom it may concern:

Be it known that we, MARSHALL F. APGAR and CHARLES B. ANDREWS, citizens of the United States, both residing in High Bridge, 5 New Jersey, have invented the following-described Improvements in Dredge-Tumblers.

This invention is an improved pulley of a type commonly known as a tumbler adapted for use in a dredging machine as the lower 10 support for the endless bucket carrier. In the manufacture and use of large dredges, many difficulties are encountered in connection with the tumbler, due primarily to the exacting requirements and conditions of 15 their use. In order to support the large loads carried by the buckets, resist abrasion by the sand, stones and water in which the tumbler works, and permit of rapid and easy raising and swinging of the parts while in 20 operation, a tumbler of large diameter, great strength, extreme hardness and the least possible weight is required.

The object of our invention is to secure these various desirable attributes in a simple 25 construction of great strength and which is particularly and specially suited for casting out of manganese steel and for the subsequent necessary heat treatment. One embodiment of our invention is illustrated in 30 the accompanying drawings although it will be evident that our invention may take various other forms. In these drawings,

Figure 1 is an end view of a tumbler embodying our invention, a portion thereof 35 being shown in transverse section;

Fig. 2 is a longitudinal section on the line II—II of Fig. 1, and

Fig. 3 is a sectional detail on the line III—III of Fig. 1.

40 The main portions of the tumbler are formed from a single casting of manganese steel or other suitable material and include a hub 10, a peripheral tread wall 11 and connections in the form of substantially parallel 45 end walls 12 which extend outwardly beyond the peripheral wall 11 as shroud flanges 13 for guiding the buckets. The casting is hollow, the interior being divided into a series of chambers spaced by partitions or webs 50 14 reinforcing the construction and serving to avoid a thickness of the tread wall greater than can be effectively produced in manganese steel.

In casting the end walls 12 a series of

comparatively large openings 15 are formed, 55 spaced apart to leave spokes, ribs, or other connecting means 16 extending from the hub to the ends of the peripheral wall 11. The openings serve for the support of the cores during casting and are comparatively 60 large to facilitate the removal of the cores as well as the circulation of water during heat treatment. To reinforce the end walls, to prevent admission of water or other material to the interior chamber, and to present substantially flush or smooth outer surfaces which will interfere as little as possible with the rotation of the tumbler in the material in which the latter works, each of 65 said openings is provided with a closure 70 plate 17 which is permanently and hermetically secured therein. Each closure plate is designed to fit its opening and seat upon a shoulder or flange 18 limiting the inward movement thereof and leaving the outer surface substantially flush with the outer 75 surface of the surrounding wall. The opening is slightly larger than the closure so as to facilitate the free insertion of the latter and to leave a groove or crevice extending 80 around its periphery when in place. Within the channel, or crevice thus produced, molten metal is introduced in a special machine and permitted to harden so as to form a permanent retaining ring 19. The introduction of such metal is accomplished by 85 means of the electric welding or similar process and results in the formation of a ring-like seam, the introduced metal thereof adhering to the sides of the crevice. The 90 shoulder 18 prevents the metal from flowing into the interior of the tumbler. The crevice extends inwardly to the shoulder 18 and its opposite side walls formed by the 95 wall of the opening and the periphery of the closure is preferably so formed as to give an effective anchorage for the cast-in-place retaining ring. The preferred way is to undercut or dove-tail the wall of the opening above the shoulder and to bevel correspondingly the periphery of the closure, the latter being of such size as to pass through 100 and leave the two proximate edge surfaces spaced apart and inclined in about the same general direction. The ring thus prevents 105 outward movement of the closure and is itself prevented from outward movement by the dove-tail formation. In this manner,

each of the openings is hermetically closed so that the entrance of any foreign material to the interior of the tumbler is prevented and the closure plates themselves, being of metal and held by the cast-in-place retaining rings, aid materially in reinforcing the entire construction.

The tumbler may be secured upon its shaft in any suitable manner, such for instance as by keys engaging with key-ways 20 which may have liners 21 of softer metal cast therein. The shaft which is shown in dotted lines in Fig. 2 may be supported at its ends by the parallel members of the boom 15 which lie adjacent to the end walls 12 of the tumbler.

We claim:

1. A tumbler having a hub portion, a peripheral wall and spaced connecting members all cast integral, a closure plate at opposite ends substantially filling the space between adjacent connecting means but leaving a crevice along the edge, and a member welded in place in said crevice for permanently retaining said closure plates.
2. A tumbler having a cast metal body including a hub, end walls each having an opening therein and a peripheral wall between said end walls and of smaller diameter than the latter to leave an annular groove or channel, closures for the openings in said end walls, each of said openings presenting a shoulder therein upon which the closure may seat, the peripheral surface of said closure being spaced from the opposed surface of the wall of the opening, and a retaining ring welded in place between and anchored to said surfaces.

Copies of this patent may be obtained for five cents each, by addressing the "Commissioner of Patents, Washington, D. C."

3. A device of the class described, including a hub, a peripheral wall presenting outwardly extending, substantially parallel terminal flanges and spokes connecting said peripheral wall and said hub, each of said openings having an outwardly facing seat or shoulder therein, and an undercut portion 45 between said shoulder and the outer surface, a closure disposed within each opening and in engagement with the seat or shoulder thereof, and having its peripheral surface outwardly beveled and spaced from said undercut portion, and a retaining ring 50 welded in place within the space between the beveled periphery of the closure and the undercut surface.

4. An article of manufacture having a body portion formed of a single piece of cast metal and including a peripheral wall, a hub and spaced, radially extending members connecting the two, and means for closing the spaces between said members to form a closed hollow chamber within said body, said means including closure plates having their outer surfaces disposed substantially flush with the outer surfaces of said members and having their side edges spaced from said members, and a retaining member welded in place in said spaces and held from outward movement by its engagement with the periphery of the opening and holding the closure against outward movement by its engagement with the periphery of the latter.

In testimony whereof, we have signed this specification.

MARSHALL F. APGAR.
CHARLES B. ANDREWS.
